UNITED STATES PATENT OFFICE.

ALFRED WANG, OF LAWRENCE, NEW YORK, ASSIGNOR OF ONE-HALF TO ROCCO CHIUSANO, OF LONG ISLAND, NEW YORK.

SYSTEM OF VALVES RELATING TO INTERNAL-COMBUSTION ENGINES.

Application filed February 9, 1927. Serial No. 166,821.

This invention relates to improvements in the system of valves for internal combustion engines, or motors, and has for its object to provide a construction of combined elements 5 that as to the results produced, in several ways will prove superior to those hitherto known, and employed.

Among the advantages of this construction is thus the attachment of this valve system to 10 the side of the cylinder, whereby said valve or valves are under no influence of the change of temperature as in case where the valve system is located in more intimate contact with the combustion chamber, and I have 15 thus eliminated the possibility of any buckling or warping of said valve with attending irregularity of motion.

Another object of my invention is to simplify the construction of a motor by eliminating 20 a number of movements, and at the same time increase the working power of said engine, and the dependability and efficiency of same.

A further object of my invention is to produce a specimen of valve that may be easily 25 replaced, or repaired, and which on account of its simplicity of construction, combination and design will prove very exact in operation, create a perfectly noiseless engine, and at the same time be very inexpensive to manufacture, as I employ a smaller number of parts 30 than is found in other motors of this type.

It is further to be pointed out as an advantage that on account of the relatively large 35 sliding surfaces of the valves exposed to wear, said wear and tear will naturally be considerably reduced and in inverse proportion to that of a poppet valve with its much smaller surface. This accordingly will admit the possibility of employing to a great extent 40 a lighter, durable metal throughout the motor, which would practically make this motor, or engine, one of lightest build, and one especially suitable to be installed in automobiles as well as aeroplanes.

45 The water-cooling system has been provided with a larger contact-surface than usually, and this has been so arranged as to equalize the temperature relative to the surroundings of said engine.

50 While I have shown and described my construction to embrace two valves suitable for motive-power engines of the reciprocatory type, and likewise shown and described a single valve for said purpose, I do consider the

latter as being the major feature of my invention. 55

With the above and other objects in view, this invention consists of the novel features of construction, combination and arrangements of parts, hereinafter fully described, 60 claimed, and illustrated in the accompanying drawings forming parts of this specification, and in which similar characters of reference indicate corresponding parts in all views and in which Figure 1 is a vertical sectional view 65 taken on line *b*—*b* of Fig. 2, illustrating an embodiment of my invention; Fig. 2 is a longitudinal sectional view taken on line *a*—*a* of Fig. 1; Figs. 3 and 4 are detail views in section; Fig. 5 is a similar view of the manifold, while Fig. 6 is an illustration, in part, 70 of actuating means, that may be applied to my device.

Referring more particularly to the drawings, 11 indicates a cylinder of an internal 75 combustion engine of the four cycle type equipped with the improved valve mechanism; 12 indicates a water jacket, and 13 an explosion chamber inclosed in the cylinder-block. 43 indicates the partition wall between the intake and outlet in the manifold. The igniter is shown at 14, and the piston 15 is joined by a connecting rod 16 to the crank-shaft 17. The cylindrical block-head may be made integral with said block or may be detachably secured to the same. 85

The single valve 28 illustrated in Figure 1 is grooved into the cylinder-block, as shown at 42 in Figure 2, in a dovetailed manner and enclosed by a casing 27, which is made integral, with the exhaust 20 and the intake 21; said casing is secured to the head by means of bolts as at 25, and to the base of the cylinder-block by means of screw-bolts, as at 26; a suitable packing is used to secure 90 the aforesaid parts together in a compact manner. The combination, as described, of the exhaust and manifold naturally simplifies the feature of an engine, and incidentally has the advantage of heating the gas supply before 100 this enters the engine. The single valve system, as illustrated, comprises a flat, rectangular shaped plate of sufficient thickness mounted in a lateral position, and at an acute angle to the cylinder-block, as shown in 105 Fig. 1. A lubricating system (not shown) is attached to the middle of the valve casing for lubricating said valves.

It is evident that the carbon produced incidental to the operation of the engine, as constructed, will add to the lubrication of the valve plates bringing about a higher compactness and thereby increasing the compression.

It will be seen that the position of the valve at an acute angle to the block admits of a straight pull on the former, a feature of 10 very great importance, and specifically claimed, being contrary to the usual manner of pulling away from the center.

The important difference between the single valve-system and the generally used double-valve system, lies in the quicker action produced on account of the specially constructed drive-system in connection with the former, making this specimen very desirable for use in high-speed motors. Said single 20 valve 28 has its lower end attached by means; for instance of bolts 34, to a reduced arm 29, terminating in a bifurcated steering head 30, the said arm carrying a cam-roller 31 adapted to engage a cam 32, by means of a 25 somewhat irregular annular, grooved projection 33 made integral with said cam, the latter is in turn mounted upon a cam-shaft operated by means of a gear mechanism.

I have in Fig. 6 illustrated another manner of operating said single valve, that is by 30 using the bell crank principle, as indicated at 35, which has its fulcrum at 36, making it possible in this case to use a smaller cam; and also multiplying the stroke by employing 35 a proportionately longer lever 37.

While the function of the engine in respect to the valve is well known and understood, I have in Figs. 3 and 4 illustrated different positions of said valve according to the 40 stage of operation, thus in Fig. 3 said valve has attained its middle position, while at Fig. 4 it is shown in a downward position. The intake and exhaust ports of said valve are indicated at 38 and 39 respectively, and the communication to the cylinder-block is shown at 40, in dotted lines.

It is obvious that changes may be made in the form, construction and arrangement of the several parts, as shown, within the scope 50 of the appended claims, without departing from the spirit of the invention, and I do not therefore limit myself to the construction and arrangement shown and described herein.

What I claim as new, and desire to secure by Letters Patent of the United States, is:

1. In an internal combustion engine, as described, the combination of a cylinder having a detachable head, and the intake and exhaust manifolds jointly arranged in an integral manner, with a single slide-valve of a substantially flat rectangular shape mounted in a dovetailed manner at an acute angle to said cylinder, in a sidewise extension formed 60 upon the block of same, the said valve being 65

provided with intake and exhaust ports and adapted to be operated from said lateral position, in conjunction with the said cylinder, and means for accomplishing said reciprocatory movements.

70

2. An internal combustion engine of the class described, comprising a cylinder-block having a detachable head and a lateral extension at one side, the latter being formed with a slanting surface and adapted to serve 75 as a seat for a flat rectangular single slide-valve mounted in said extension in a dovetailed manner at an acute angle; inlet and exhaust ports registrable with those of the cylinders; an abutting countersection rigidly, but detachably, connected to the said side of the cylinder-block and comprising adjoining intake and exhaust manifolds in conjunction with a coverplate for said valve, and means for reciprocating the latter substantially as and for the purpose set forth.

3. In an internal combustion engine, a cylinder comprising a cylinder-block provided with a detachable head, the said block and head being at one side provided with an extension formed in an oblique manner for cooperation with a single plate valve, similarly positioned longitudinal grooves formed in a dovetailed manner at each side of the extensions of the block and head respectively, 90 for the purpose of receiving and retaining the said single valve during operation; a separate integral section formed with an inner surface coinciding in shape with the said lateral extension and comprising intake and 95 exhaust manifolds, the said integral section being elongated in an up and downward direction to form a cover for the said single valve, and means for connecting the said separate integral section to the block and to 100 the head of the cylinder respectively.

4. An internal combustion engine comprising a cylinder block with a detachable head, the said block and head being provided with a plurality of water-cooling compartments 110 independently arranged; a lateral projecting section arranged at one side of and being integral with the said block and head, respectively, substantially dovetailed longitudinal grooves arranged in the said block and head 115 and adapted to receive and retain a single valve during operation, a detachable side member arranged with in- and outlet manifolds and formed with an inner flat surface adapted to cover the said single valve, and 120 means for securely attaching the said side member to the lateral projecting section, substantially as shown and described.

5. An internal combustion engine comprising a cylinder-block and head, a piston operating in said cylinder, a plurality of water-cooling compartments independently arranged in the said block and head, a lateral projecting section arranged at one side of, and being integral with the said block and 125 130

head respectively, substantially dovetailed longitudinal grooves arranged in the said block and head and adapted to receive and retain a single valve during operation; a 5 detachable side member arranged with in- and outlet manifolds and formed with an inner flat surface adapted to shield the said single valve, and form a casing with the lateral projecting section, and means for securely connecting the latter two parts together, substantially as shown and described.

6. In an internal combustion engine, the combination of a cylinder, a piston, and at one side of the former a longitudinal extension provided with a surface at an acute angle and adapted for cooperation with a single slide valve in order to facilitate the means arranged for exerting a straight pull upon the said valve; intake and exhaust ports 15 arranged in said longitudinal extension and single valve, respectively, a reduced arm rigidly attached to said single valve and terminating in a bifurcated steering head, a cam-roller attached to said arm and adapted 20 to engage a cam by means of an irregular, annular, grooved projection formed integrally upon the latter, which in turn is mounted upon a cam-shaft driven by a gear mechanism, substantially as shown and described.

7. In an internal combustion engine, a cylinder-block comprising a plurality of sections, being at one side formed with a longitudinal extension projecting above the end 35 of the said cylinder and provided with a flat slanting surface having intake and exhaust ports arranged therein, grooves longitudinally formed in the said extension and adapted to receive a single, obliquely positioned, flat slide-valve formed with flaring side-edges in order to make a comparatively

tight fitting with the said grooves during operation, in- and outlet openings provided in the said single valve, a detachable section, embracing means for the intake and exhaust 45 manifolds arranged together, and forming with its elongation in up- and downward direction a coverplate adapted to snugly fit the oblique surface of the said extension, thereby forming an enclosure with the latter for protection of the said single valve.

8. An internal combustion engine, comprising a cylinder-block and head, a longitudinal extension integral with and formed at one side of the said block and head, respectively, at an acute angle; the said extension being provided with intake and outlet ports registering with those of a single flat valve, the latter being adapted to engage the said extension in a slidable manner; longitudinal somewhat dovetailed grooves formed in the said extension and arranged to receive and retain the edge portions of the said valve during operation; a covering member substantially shaped as the surface of 60 the said lateral extension and being adapted to form an enclosure therewith for protection of the said valve, means for connecting the said enclosure with the sidewise extension, and means for actuating the said single valve 65 and comprising a reduced arm rigidly attached to said single valve and terminating in a bifurcated steering head, a cam-roller attached to said arm and adapted to engage a cam by means of an irregular, annular 70 grooved projection formed integrally upon the latter, which in turn is mounted upon a cam-shaft driven by a gear mechanism, substantially as shown and described.

In testimony whereof I have hereunto 75 affixed my signature.

ALFRED WANG.
